UNITED STATES PATENT OFFICE.

JOHN HENRY FOSS, OF PASSAIC, NEW JERSEY.

INSIDE SHOE

SPECIFICATION forming part of Letters Patent No. 520,417, dated May 29, 1894.

Application filed February 17, 1894. Serial No. 500,516. (No model.)

To all whom it may concern:

Be it known that I, JOHN HENRY FOSS, a subject of the Emperor of Russia, residing in Passaic, in the county of Passaic, in the State 5 of New Jersey, have invented a certain new and useful Improvement in Inside Shoes, of which the following is a specification.

My improved shoe is adapted to be used inside of larger boots or shoes of ordinary construction as an extra protection in cases where the feet are to be exposed to very great cold with little exercise, as horse-car drivers and lumbermen. The shoe gives a double covering for the toes with unusual 15 facility for yielding to match different shapes of feet and to accommodate the motions. In its most complete form I provide a loose flap, which may be arranged to lie under or over the toes as the severity of the weather may 20 require. When this flap is raised it makes a triple extra protection for the toes of the wearer,—two thicknesses of the shoe proper, and one thickness of the flap.

I make this shoe of thin material, having 25 high non-conducting properties, preferably gut, limbered and perforated.

The accompanying drawings form a part of this specification and represent what I consider the best means of carrying out the invention.

Figure 1 is a perspective view. Fig. 2 is a central longitudinal section, and Fig. 3 a transverse section.

Similar letters of reference indicate corresponding parts in all the figures where they appear.

A is an inner sole and B an outer sole, each very thin but of an ordinary form.

D', D², are the two parts of the "upper," 40 joined together by a seam extending up and down at the heel. The peculiarities in the construction are at the front. The two portions D', D², are separate and distinct, and lie one over the other at the toe. Except at 45 the rear these parts D', D², are not joined together. I will designate the overlapping portion of each part as D³. Each is joined to the sole around the whole front of the shoe.

E is a loose flap attached to the sole within the shoe, so arranged that it may lie either 50 on the surface of the in-sole with the toes over it, or may lie along the under side of the over-lapped part D³ with the toes under it. Its length is sufficient to reach up on the instep, covering the foot further than the 55 parts D', D².

My shoe may be used either inside or outside of the stocking, the choice depending somewhat on the relation of the size to the 60 foot. In either position it adds but little to the thickness of the foot-covering, but contributes greatly to the warmth. If the weather is very severe, the flap E is raised and the foot inserted under it. If the weather is more moderate, the flap E is depressed and 65 laid on the in-sole, and the foot placed over it. Under either condition there is the double covering of the toes due to the overlapping of the parts D', D² over the whole surface D³.

The preferable material for all the parts of my shoe is gut or bladder, limbered by rolling or suitable mechanical treatment. The front portion of the shoe, especially 75 where the material is double, should be perforated, as indicated by d, to allow the escape of perspiration. I propose to join the parts to the sole by cement, but owing to the peculiar nature of the material I prefer with all cements with which I have experimented 80 to employ also at each junction a line of stitching.

The shoe may serve with some success as an ordinary slipper for in-door use.

Modifications may be made without departing from the principle or sacrificing the advantages of the invention. I can extend or restrict the parts so that the over-lap D³ will be wider or narrower. Parts of the invention can be used without the whole. I can 90 omit the flap E.

I claim as my invention—

1. In a shoe of thin material adapted for use inside of an ordinary shoe or boot, the two parts of the upper held separate and distinct at the front and attached each inde-

pendently to the sole, with a portion at the toe overlapped, as herein specified.

2. An inside shoe of gut, flexed and perforated and formed with the two sides of the upper extended independently to the front and overlapping each other, as herein specified.

In testimony that I claim the invention above set forth I affix my signature in presence of two witnesses.

JOHN HENRY FOSS.
